UNITED STATES PATENT OFFICE.

CHARLES E. ROYCROFT, OF COVINGTON, KENTUCKY, ASSIGNOR TO THE GLOBE-WERNICKE COMPANY, OF CINCINNATI, OHIO, A CORPORATION OF OHIO.

FOLLOWER FOR FILING-CABINETS.

1,237,824.

Specification of Letters Patent. Patented Aug. 21, 1917.

Application filed March 29, 1916. Serial No. 87,656.

To all whom it may concern:

Be it known that I, CHARLES E. ROYCROFT, a citizen of the United States, residing at Covington, in the county of Campbell and State of Kentucky, have invented certain new and useful Improvements in Followers for Filing-Cabinets, of which the following is a full, clear, and exact description, reference being had to the accompanying drawings, forming part of this specification.

The object of my invention is to produce a follower, the parts of which are preferably made of sheet metal and can be produced and assembled at very low cost, which is capable of holding the contents of the file, when compressed, firmly in position against accidental displacement, and which when released can be easily moved backward or forward in the file without binding, and the preferred embodiment consists in the combination and arrangement of the parts as described in the specification, shown in the accompanying drawings and pointed out in the claims.

The drawers of most filing cabinets are provided in their bottoms, at or about the middle, with a channel of sufficient width and depth to accommodate the tongues of guides which are usually employed to separate the contents of the files for convenience in filing and finding papers and I prefer to construct my follower so that the binding parts are located within this channel, although this is not essential, and other suitable arrangements can be made without departing from the spirit of my invention.

In the accompanying drawings—

Figure 1, Sheet 1, is a perspective view of the front portion of the drawer of a filing cabinet showing the follower clamped in position against the contents of the file, the drawer being broken away immediately behind the follower to show the arrangement of the parts.

Fig. 2, Sheet 1, is a rear elevation of the follower and the channel of the drawer of a filing cabinet which contains the track upon which the follower is operated.

Fig. 3, Sheet 1, is a sectional end elevation of the follower removed from the drawer, on the line 3—3 of Fig. 2.

Fig. 4, Sheet 2, is an end elevation, partly in section, of the follower, removed from the drawer of the filing cabinet, showing the positions of the clamping parts when it is locked in position, in solid lines, and their positions when released, in dotted lines.

Fig. 5, Sheet 2, is an enlarged broken front elevation of the follower.

Fig. 6, Sheet 2, is a portion of a follower corresponding with Fig. 4, but showing a modification of the device in which the rollers which act as a clamping device also serve as a bearing for the follower, when the clamping lever is compressed and the parts are in the position shown by the dotted lines.

Fig. 7, Sheet 2, is a portion of a front elevation, corresponding with Fig. 5, also showing the modification illustrated in Fig. 6.

The same numerals of reference indicate identical parts in all the figures.

In the drawings the drawer of the filing cabinet is represented as having a front 1, with sides 2, and a bottom 4, provided with the usual or any suitable channel 5.

Suitably mounted within this channel 5 is a track 6, preferably made of sheet metal and provided with a flange 7 on each edge, with a slight clearance underneath it to accommodate the guides of the follower.

The follower consists of a body or main portion 8, of the proper size to compress the contents of the drawer, preferably made of sheet metal and provided with a top flange 9, side flanges 10, 10, and a bottom flange 11.

These flanges are provided to give additional strength to the body 8 and to present a more finished appearance. I prefer to taper the side flanges 10 as shown, and make the bottom flange 11 sufficiently wide to provide a substantial lower surface to which to secure the housing carrying the clamping mechanism.

This housing is preferably of sheet metal and consists of a top plate 12, the underneath top surface of which slants forwardly so that it is deeper at the rear than at the front, and side plates, 13, 13, provided with flanges 14, 14, adapted to engage the under surface of the flanges 7, 7, of the track 6.

The side plates 13, 13, are provided with forward lower extensions 15, 15, and rearward lower extensions 16, 16, to provide a greater bearing surface on the flanges 7, 7, 5 of the track 6, although these extensions are not essential, and in the modification shown in Figs. 6 and 7 the rearward lower extensions 16, 16 are omitted. At the ends of the lower extensions I provide an over- 10 turned flange 17, adapted to engage the upper surface of the flanges 7, 7, of the track 6 to coact with the flanges 14 and hold the follower in position on the tracks.

Between the lower flanges 14 and the 15 upper flanges 17 of the side plates 13 of the housing, sufficient space is provided to accommodate the flanges 7 of the track 6 so that when the clamping mechanism is released the follower can be readily moved 20 on the track 6, backward to permit the operator to manipulate the contents of the file, or forward to compress the contents of the file.

In attaching the housing to the lower 25 flange 11 of the body of the follower, I prefer to make this flange 11 conform with the upper surface of the top plate 12, as shown more clearly in Figs. 2, 3 and 4, it being understood that the housing can be 30 either welded, riveted or otherwise securely fastened to the flange. Movable attached to the body of the follower 8, preferably by means of rivets 18, is a sheet metal clamping lever 19, normally held in the position 35 indicated by the solid lines in Fig. 4 by means of a suitable spring 20. The lower portion of this clamping lever 19 is bent rearwardly as at 21, thence downwardly as at 22, and forwardly as at 23 to clear the 40 lower flange 11 of the body 8 and the top plate 12 of the housing, the cut out portion, indicated at 24 allowing free passage for the usual or any suitable rod in the channel 5 of the drawer upon which the guides are 45 strung, and providing two forwardly extending arms 25, 25, each of which is provided at its forward end with a loop, 26, furnishing means for carrying a stud 27, upon which is rotatably mounted a roller 50 28. If preferred the rod for the guides might be dispensed with and the roller 28 mounted between the forwardly extending arms 25, 25, or arranged in any other suitable manner.

55 When the clamping lever 19 is released, the pressure of the spring 20 forces the lower portion of the lever forward and the rollers 28, contact with the forwardly slanting under surface of the top plate 12 of the 60 housing and the upper surfaces of the flanges 7, 7 of the follower track 6 which through the coöperation of the flanges 14, 14 of the side plates 13, 13 of the housing securely clamp the follower against rear-

ward movement, although a forward movement is permitted on account of the formation and relation of the parts.

To release the follower the upper portion of the clamping lever is compressed, and this action carries the lower portion of the lever backward, breaking the contact of the rollers 28 with the under surface of the top plate 12 of the housing and the upper surface of the flanges 7, 7 of the follower track 6 and permitting the follower 75 to be freely moved either forward or backward upon the track 6 without binding.

In the modification shown in Figs. 6 and 7, Sheet 2, I have dispensed with the rearward lower extensions 16, 16 and have provided in each of the side plates 13 of the housing an elongated slot 29, enlarged at its forward end and through these slots I extend the ends of the studs 27 which carry the rollers 28. In this construction, when 85 the clamping lever 11 is compressed to release the follower, the rollers 28 are carried back out of contact with the under surface of the top plate 12 of the housing, and guided by the elongated slots 29 into 90 which the ends of the studs 27 extend, remain in contact with the flanges 7 of the follower track 6 and serve as roller bearings upon which the follower can be freely operated, eliminating the tendency of the 95 follower to chatter on the track when being operated in a careless manner.

The slots 29 are shown enlarged at their forward ends to permit the rollers, when in contact with the flanges 7 of the track 6 100 and the under surface of the top plate 12 of the housing to conform to any slight unevenness of the parts and insure contact of all the clamping parts when the clamping lever is released.

105 It will be understood that I do not confine myself strictly to the details herein shown and described, and that other forms might be provided without departing from the spirit of my invention.

110 Having thus fully described my invention I claim:

1. A follower comprising a body, a housing provided with side plates adapted to movably engage a track in the drawer of a filing cabinet, and a clamping lever carrying means adapted to lock the follower against movement when brought into engagement with said housing and said track and to act as a bearing upon which the follower may be freely moved backward or forward without binding when disengaged from the housing.

115 2. A follower comprising a body, a housing provided with side plates adapted to engage a track or guideway in the drawer of a filing cabinet, and a clamping lever carrying rotary means for locking the fol-

lower against movement when brought into engagement with said housing and said track or guideway by means of pressure applied against said clamping lever.

5 3. A follower comprising a body, a housing provided with side plates adapted to engage a track or guideway in the drawer of a filing cabinet, and a clamping lever carrying rotary means for locking the follower against movement when brought into engagement with said housing and said track or guideway.

10 10. A follower comprising a body provided with flanges on its top, bottom and sides, a housing consisting of a top plate and vertical side plates provided with means for movable engagement with a track or guideway in the drawer of a filing cabinet, and a clamping lever provided with clamping means adapted to lock the follower against movement when disengaged from the housing, by means of pressure applied to engage or disengage the parts through the medium of the clamping lever.

15 4. A follower comprising a body provided with flanges on its top, bottom and sides, a housing consisting of a top plate and vertical side plates provided with means for movable engagement with a track or guideway in the drawer of a filing cabinet, and a clamping lever provided with clamping means adapted to lock the follower against movement when brought into engagement with the top plate of said housing and said track or guideway.

20 25 30 35 40 5. A follower comprising a body provided with flanges on its top, bottom and sides, a housing consisting of a top plate and vertical side plates provided with means for movable engagement with a track or guideway in the drawer of a filing cabinet, and a clamping lever provided with clamping means adapted to lock the follower against movement when brought into engagement with the top plate of said housing and said track or guideway and to act as a bearing upon which the follower may freely move backward or forward without binding when disengaged with the top plate of said housing.

45 6. A follower comprising a body provided with flanges on its top, bottom and sides, a housing consisting of a top plate and vertical side plates provided with means for movable engagement with a track or guideway in the drawer of a filing cabinet, and a clamping lever provided with roller bearings mounted on studs constituting clamping means adapted to lock the follower against movement when brought into engagement with the top plate of said housing and said track or guideway.

50 55 60 7. A follower comprising a body provided with flanges on its top, bottom and sides, a housing consisting of a top plate and vertical side plates provided with means for movable engagement with a track or guideway in the drawer of a filing cabinet, and a clamping lever provided with roller bearings mounted on studs constituting clamping

means for locking the follower against movement when brought into engagement with the top plate of said housing and said track or guideway, and to constitute a roller bearing upon which the follower may be freely moved backward or forward on the 70 track or guideway without binding when disengaged from the top plate of said housing.

8. A follower comprising a body provided with flanges on its top, bottom and sides, a housing consisting of a forwardly slanting top plate and vertical side plates provided with flanges adapted to movable engagement with a flanged track or guideway in the drawer of a filing cabinet and a clamping lever provided with roller bearings mounted on studs constituting clamping means adapted to lock the follower against movement when brought into engagement with the forwardly slanting top plate of said housing and said flanged track or guideway.

9. A follower comprising a body provided with flanges on its top, bottom and sides, a housing secured to said body consisting of a forwardly slanting top plate and vertical side plates provided with flanges adapted for movable engagement with a flanged track or guideway in the drawer of a filing cabinet, a spring-actuated clamping lever provided with roller bearings mounted on studs constituting clamping means adapted to lock the follower against movement when brought into engagement with the forwardly slanting top plate of said housing and said track or guideway and to constitute a roller bearing upon which the follower may be freely moved backward or forward without binding when disengaged from the forwardly slanting top plate of said housing and guiding means for the studs carrying the roller bearing to hold said roller bearings in a rigid vertical position when disengaged from the forwardly slanting top plate of said housing.

10. A follower comprising a body provided with flanges on its top, bottom and sides, a spring actuated clamping lever having a forwardly extending lower portion provided with rotary clamping means, a housing secured to the bottom flange of said body consisting of a forwardly slanting top plate and vertical side plates provided with flanges to movably engage the lower and upper surfaces of a flanged track or guideway in the drawer of a filing cabinet and provided with elongated slots, and studs carrying the rotary clamping means of said spring actuated clamping lever guided in said elongated slots to control the movement of the rotary clamping means which when at their foremost position engage the upper surface of the flanges of the track or guide-

way and the lower forwardly slanting surface of the top plate of the housing and lock the follower securely against backward movement, and when at their rearmost position are free from engagement with the lower forwardly slanting surface of the top plate of the housing but engaged with the upper surface of the flanges of the track to

act as a bearing upon which the follower can be freely moved forward or backward 10 without binding.

CHARLES E. ROYCROFT.
